UNITED STATES PATENT OFFICE.

CORNELIUS P. SULLIVAN, OF MEDFORD, AND HENRY B. BLACK, OF EVERETT,
MASSACHUSETTS.

BALLOT-BOX.

No. 926,779.

Specification of Letters Patent.

Patented July 6, 1909.

Application filed June 12, 1908. Serial No. 438,033.

To all whom it may concern:

Be it known that we, CORNELIUS P. SULLIVAN, of Medford, and HENRY B. BLACK, of Everett, both in the county of Middlesex and State of Massachusetts, citizens of the United States, have invented an Improved Ballot-Box, of which the following is a specification.

Our ballot box is of the kind with which the ordinary balls and cubes are used to take a ballot upon a particular question. Where such ballot boxes are used, as the ballot is secret it has been impossible heretofore to tell whether a person through accident or on purpose has deposited two ballot balls. Moreover in organizations where each member is required to vote it has been impossible to tell whether such requirement has been fulfilled.

Our invention is intended to provide a ballot box in which but one ballot ball can be cast at a time and in the casting of such ballot ball an audible and unmistakable sound is made which indicates that a ballot ball has been cast.

Our invention will be understood by reference to the drawings in which—

Figure 1 is a vertical section of the ballot box, the mechanism peculiar to our invention being shown in elevation. Fig. 2 is a similar view in which, however, the mechanism embodying our invention is shown in vertical section, and Fig. 3 is a vertical section of the said mechanism in action.

A is the floor of the ballot box which has side and end walls, a drawer A¹ located to receive the ballot balls which have been cast, an opening A² through which the hand may be passed when about to cast a vote, and a top A³. It will be noted that the only way of reaching the interior of the box is through the hand opening A² or through the removal of the drawer A¹. We have shown over the drawer an opening A⁴, which is covered with a fine wire netting for a purpose to be herein-after stated. The ballot box is divided into two chambers B, B¹ by a partition B², B³, B⁴, the parts B², B⁴ being substantially vertical though out of line with each other and the part B³ connecting the two parts B² and B⁴.

Upon the floor of the ballot box and passing up through the partition B³ is a guide-way comprising as shown a tube C attached to the floor A of the box by screws or other-

wise. In this tube slides a gate D. The tube C has two orifices preferably located opposite each other, one orifice c carrying a delivery tube E leading into the chamber B¹ so that those ballot balls which are placed within the tube are delivered into the drawer A¹. The orifice c¹ upon the opposite side of the guide-way opens into the chamber B of the ballot box so that a ballot ball may be deposited in the gate and a second ball may fall back into that chamber B as below described.

The gate D is supported within the guide-way C by a spring d which it partially encloses. As shown a pin d¹ passes through the gate D and rests upon the spring d so that when the gate is depressed the spring will be compressed. The gate D also has two orifices located opposite each other, one of which d² is normally out of register with the delivery tube E while the other d³ is always in register with the opening c. The top of the gate D is provided preferably with a block d⁴ by means of which the gate may be depressed by the finger when the ballot is to be cast. Above the orifice d² the edge of the gate is preferably sharpened to form a knife edge for reasons hereinafter described.

The lower edge of the orifice d² carries a tongue d⁵ which is hinged thereto and is preferably shaped to receive a ball or other ballot. This tongue extends across the gate and serves to receive and support a ballot before it is cast into the chamber B¹. Below this tongue d⁵ lies a finger c² attached to the inside of the guide-way and so arranged that when the gate is depressed the tongue will be lifted by this finger and thrown over into the position shown in Fig. 3, thus depositing the ballot ball in the delivery tube E through which it falls into the chamber B¹. A bell F suitably hung lies in the path of the ballot ball so that with each ballot ball discharged from the tube there is a sound of the bell and it is thus impossible for a person to pretend to vote without being found out for unless he votes the bell will not ring. The opening A⁴ referred to above is located over this bell to allow the sound to escape from the interior of the box. The orifice d³ in the gate not only allows the voter to place a ballot ball upon the tongue in the act of voting but when the gate has been depressed as shown in Fig. 3 this opening registers with a portion of the opening c¹ in the guide-way.

It will be noted that when the apparatus is in the position shown in Fig. 3 the entrance to the delivery tube E is closed so that a second ball cannot be voted until the parts have resumed their original position, and it will also be noted that at this movement orifice d^3 registers with a portion of the orifice c^1 in the guide-way. Because of this construction it is impossible for one person to cast 10 two ballots at one operation, for suppose he attempts to place two balls one on top of the other in the gate D and depresses the gate, the lower ball will be deposited in the delivery tube by the action of the finger c^2 upon 15 the tongue d^5 , and at the same time the upper edge of the orifice d^2 will cut in between the top ball and orifice c closing the orifice with the tongue d^5 and forcing the upper ball back into the chamber B through the orifices d^3 20 and c . We prefer also to attach to the gate a register of any ordinary description which will register the number of depressions or downward movements of the gate and thus indicate at the end of the balloting how 25 many ballot balls have been cast. Such a register is shown at G mounted on top of the box, its arm g being actuated by a connecting rod g^1 which connects with a pin g^2 attached to the gate D through a slot g^3 in the side of 30 the guide-way by means of a clamp piece g^4 . In using the ballot box above described the person puts his hand into the chamber B and taking a ballot ball drops it on the tongue d^5 through the orifices c , d^3 . He then de- 35 presses the gate by means of the block d^4 , which allows the opening d^2 to register with the corresponding opening c in the guide-way and also causes the lifting of the tongue d^5 , so that it throws the ballot ball out into 40 the tube E. The momentum of the ball carries it against the bell F so that knowledge is conveyed that the ballot ball has been deposited in the drawer A¹. At the same time the depression of the gate D causes the 45 register G to register one vote. Upon removing the finger from the block d^4 the gate returns to its original position. Should the voter deposit two balls in the gate and then depress the gate the lower ball will be thrown 50 into the delivery tube E as shown in Fig. 3 but as the upper edge of the orifice d^2 of the gate and the tongue d^5 close the entrance to the delivery tube E so that only one ballot ball can pass out, the other ball will be 55 thrown out in the opposite direction through the orifice d^3 of the gate and the orifice c^1 in the guide-way back into the chamber B. Thus it will be impossible for one person at 60 one operation to cast two ballots and every ballot cast not only gives information by striking the bell that it is cast, but also is registered through the instrumentality of the depressed gate and the register located in sight on top of the ballot box.

65 The register may be of any one of the well

known constructions such as are used for registering the rotations of shafts in ordinary machinery or preferably the small cyclometer used with bicycles and for like purposes. Such an apparatus being well known 70 in its construction is not here explained. By the use of the bell arranged as shown it is impossible for a person to pretend to vote without being discovered for unless he votes the bell will not sound and the teller will 75 know that a vote has not been cast. In addition to this feature we believe that our ballot box is the first in which the act of voting closes the voting passage after the vote has been cast and so prevents the casting of 80 another vote until the registering and other apparatus have resumed their normal position, and in no other ballot box so far as we know is a second ball thrown back into the original chamber under such circumstances. 85

We have used the word ball in the foregoing specification to indicate either ball or cube or whatever form may be considered best for ballots.

What we claim as our invention is:

1. A ballot box comprising a chamber for receiving the ballot balls voted and means adapted to communicate with said chamber whereby only one ballot ball can be voted at a time and a second ballot ball in contact 95 with the first will be thrown out from the ballot-casting mechanism.

2. A ballot box comprising a ballot ball receiving chamber, and a single means adapted to communicate with said chamber whereby only one ballot ball can be voted at a time and a second ballot ball in contact with the first will be thrown out, and means for indicating the arrival of the ballot ball in 100 said chamber said means comprising a bell located in the path of the ballot ball and adapted to be struck by it as it falls into the receiving chamber.

3. A ballot box comprising a ballot ball receiving chamber, and a single means 110 adapted to communicate with said chamber whereby only one ballot ball can be voted at a time and a second ballot ball in contact with the first will be thrown out, and means for recording the number of the vote cast and 115 means operated by the ballot ball whereby an audible signal will be given as the ball reaches the receiving chamber.

4. In a ballot box, means for preventing the casting of more than a single ballot ball 120 at a time comprising a receiving chamber, an orifice in one wall thereof, means for holding a ballot ball, and means normally closing said orifice and being adapted to be moved to open said orifice and allow said 125 ballot ball to pass therethrough and means adapted to prevent a second ballot from immediately following said first ballot and to throw out said second ballot from the ballot-casting mechanism.

5. In a ballot box, means for preventing the casting of more than a single ballot ball at a time comprising a receiving chamber, an orifice in one wall thereof, means for holding a ballot ball, said means normally closing said orifice and being adapted to be moved to open said orifice and means adapted to cause said ballot ball to pass therethrough.

6. In a ballot box, means for preventing the casting of more than a single ballot ball at a time comprising a receiving chamber, an orifice in one wall thereof, a ball receptacle provided with an orifice in one side thereof, said ball receptacle being movable whereby 15 its orifice may be caused to register with the orifice in the wall of said chamber, said receptacle having a tongue to support said ball and means for causing said tongue to throw said ball through said orifice.

20 7. In a ballot box, a receiving chamber, a guide-way connected with said chamber, and having an orifice leading into said chamber, a ballot ball receptacle movable in said guide-way and having an orifice normally closed 25 but capable of registration with said guide-way orifice, and means adapted to cause the registration of said orifices to receive one ballot and simultaneously to throw out a second ballot attempted to be cast with said first 30 ballot.

8. In a ballot box, a receiving chamber, a guide-way having orifices on opposite sides

thereof, one of said orifices leading into said receiving chamber, a gate provided with two orifices, one on each side thereof, and adapted to register with the orifices in said guide-way, and means for keeping the orifice in said gate normally out of register with said orifice in said guide-way, means operable when said orifices are in register whereby a 35 ballot ball will be thrown into said receiving chamber and a second ballot ball located on said first ballot ball will be thrown out through the opposite orifice.

9. In a ballot box, a guide-way having orifices on opposite sides thereof, a gate having orifices on opposite sides thereof, normally out of register with but adapted to be caused to register with the orifices in said guide-way, said gate having a movable tongue, and said 50 guide-way having a finger whereby said tongue will be raised on the depression of the gate to throw a ballot ball located thereon out through one of said orifices, said depression of said gate causing the orifices on 55 the opposite side of it and in said guide-way to register and allow the exit of a second ball, as set forth.
